UNITED STATES PATENT OFFICE.

LEWIS A. FOLSOM, OF DALTON, GEORGIA.

AUTOMATIC FIRE-EXTINGUISHER.

SPECIFICATION forming part of Letters Patent No. 228,621, dated June 8, 1880.

Application filed January 14, 1880.

To all whom it may concern:

Be it known that I, LEWIS A. FOLSOM, of Dalton, in the county of Whitfield and State of Georgia, have invented a new and Improved 5 Automatic Fire-Extinguisher, of which the following is a specification.

The drawing represents a vertical sectional central elevation of the device.

The object of this invention is to provide a 10 simple and efficient apparatus for extinguishing fires.

The invention consists of two barrels or other vessels, set one within the other, the outer one containing sulphuric or other acid, 15 and the inner one carbonate of soda or other alkaline carbonate, into which latter vessel a third vessel, containing gunpowder or other explosive, is introduced, said explosive vessel having a fuse or tube filled with powder connected with it and extending upward through the cover of the other vessels, so that fire applied to the said tube or fuse will be communicated to the explosive in the interior vessel, and cause an explosion which will burst asunder the containing-vessels, and thereby cause 25 their contents to mingle, by which means a sufficient volume of carbonic-acid gas will be generated to extinguish the fire.

In the drawing, A represents the outer barrel or vessel for containing the acid, preferably sulphuric acid. B is a smaller vessel for holding the alkali, preferably bicarbonate of soda. C is the interior vessel for holding the gunpowder or other explosive, and D is the 35 fuse or tube communicating with the said vessel C and passing upward out of the cover E of the device.

The apparatus charged as described may be placed in any room where a fire is likely to occur.

Powder and other combustible material is placed upon the top of the cover E, so that it may be quickly ignited on the breaking out of

the fire, and when the combustible material on the cover of the vessel is ignited the fire communicates at once, through the tube or fuse D, with the powder in the vessel C and causes an explosion, which will instantly shatter both containing-vessels A and B, and mix and throw the acid and alkali in every direction about the 45 room, thus forming carbonic-acid gas in sufficient quantity to extinguish any fire at once.

The device is especially designed for cotton-gin houses, where fire may occur at any moment from friction of machinery, &c., and 50 where a fire would burn so rapidly that it would be practically impossible to supply water fast enough to extinguish it soon enough to save any of the contents of the building, or indeed, the building itself. I would place this 55 apparatus, charged as above set forth, near the ceiling of the lint-room in a gin-house, so that should a fire break out it would instantly communicate to the fuse and explode the apparatus.

Should this device be placed for use in a dwelling-house, and should the house take fire, some one might proceed at once to the room or closet containing the device and set fire to the fuse with a match or candle, and then retire, when soon the explosion would occur that would supply enough carbonic-acid gas to put 65 out the fire in the house.

Having thus described my invention, I claim as new and desire to secure by Letters Patent—

A fire-extinguishing apparatus consisting of the acid, carbonate, and explosive vessels A B C, respectively, set one within another, and provided with cover E and tube D, substantially as and for the purpose described.

LEWIS AURELIUS FOLSOM.
